DESIGN FOR A STEMMED GOBLET OR SIMILAR ARTICLE

William P. Morrison, Mount Pleasant, Pa., as-
signor to Bryce Brothers Company, Mount
Pleasant, Pa., a corporation of Pennsylvania

Application March 6, 1940, Serial No. 90,720

Term of patent 14 years

To all whom it may concern:

Be it known that I, William P. Morrison, a citizen of the United States and residing at Mount Pleasant, in the county of Westmoreland, and State of Pennsylvania, U. S. A., have invented a new, original, and ornamental Design for a Stemmed Goblet or Similar Article, of which the following is a specification, reference being had to the accompanying drawing, forming a part thereof, wherein:

Figure 1 is a view in elevation of a stemmed goblet, showing my new design; and

Figure 2 is a sectional view, taken on line II—II of Figure 1.

It is to be understood, however, that while I have illustrated the design of my invention as applied to a goblet, it is equally applicable to a complete line of stemmed glassware in addition to goblets.

I claim:

The ornamental design for a stemmed goblet or similar article, substantially as shown and described.

WILLIAM P. MORRISON.
